UNITED STATES PATENT OFFICE.

GEORGE A. SPEAR, OF MEDFORD, MASSACHUSETTS, ASSIGNOR, BY MESNE ASSIGNMENTS,
TO THE FLINTKOTE COMPANY, OF BOSTON, MASSACHUSETTS, A CORPORATION OF
MASSACHUSETTS.

SHEET MATERIAL FOR INNERSOLES.

1,312,758.

Specification of Letters Patent. Patented Aug. 12, 1919.

Application filed March 10, 1917. Serial No. 153,805.

To all whom it may concern:

Be it known that I, GEORGE A. SPEAR, a citizen of the United States, residing at Medford, county of Middlesex, State of Massachusetts, have invented an Improvement in Sheet Materials for Innersoles, of which the following description, in connection with the accompanying drawing, is a specification, like characters on the drawing representing like parts.

This invention relates to the composition of a new material in sheet form for use in innersoles for shoes.

The material which is in sheet form is designed to be cut up into innersoles for shoes either of the Mackay, standard screw or nail type or of the Goodyear type. In the former case the innersole and other superimposed parts of the shoe are united together by through and through stitches, by standard screws or by nails or pegs and the material is peculiarly suited for this purpose. In the latter case the innersole and other superimposed parts of the shoe are united by stitching and for this purpose the innersole is provided with a separate rib secured thereto by stitching or in any other suitable way.

The object of the invention is to produce a material which shall be tough, flexible, substantially sweat and waterproof, which shall not be subject to decay or deterioration, which shall secure the thread, nails or pegs employed in the manufacture of the shoes, which shall be capable of being made into a Goodyear innersole by the addition of a suitable rib, and which shall produce a cheap and satisfactory innersole.

The invention resides in a material in sheet form made up of a plurality of sheets cemented together, the intermediate sheet being a compressed sheet of tar or asphalt saturated felt presenting a cementitious water repellent surface and the outer or surface sheets which are cemented thereby to the intermediate sheet being of napped or woven material. The nature of the invention will appear more fully from the accompanying description and drawings and will be particularly pointed out in the claim.

In the drawings,

Figure 1 is a top plan view of an inner-

sole of the Goodyear type embodying the invention;

Fig. 2 is a transverse cross section of the 55 construction shown in Fig. 1;

Fig. 3 is a plan view of an innersole of the Mackay type;

Fig. 4 is a transverse cross section of the 60 construction shown in Fig. 3.

The innersole material from which the innersoles illustrated are made is a composite sheet material.

The inner sheet which may itself be made 65 of one or more layers is a compressed sheet of tar or asphalt saturated felt. This material which is the base of the innersole is made of rags, jute, paper, pulp or other similar material compressed between heated 70 rolls and filled with an asphalt preparation at the same time and is generally known on the market as tar or asphalt saturated felt.

The surface sheets of the innersole material are of a woven or closely felted fabric. 75 These sheets give to the intermediate sheet the necessary strength and toughness and provide the necessary finish for the exterior of the material.

In the construction shown in Figs. 1 and 2 80 the inner sheet of compressed tar or asphalt saturated felt is shown as reinforced at the opposite surfaces by sheets of canvas, drilling or sheeting cemented thereto. This gives a very finished product and the sheet 85 material thus produced is of a firm, tough character and substantially waterproof by reason of the waterproof nature of the intermediate sheet. This fabric is peculiarly adapted for use in the manufacture of 90 Goodyear innersoles which may be done by securing to the surface of the innersole a rib 1 herein shown, for example, as a cord rigidly secured to the innersole in any well known and familiar manner such as by 95 stitching.

In the construction shown in Figs. 3 and 4 the innersole material is faced at one side with canvas, drilling or sheeting and at the opposite side with a closely felted or heavily 100 napped fabric. This secures a material similar to that illustrated in Fig. 2 but with the addition that the one surface covered with the napped fabric is of such a character that it presents at the same time a soft 105

and comfortable surface to the foot of the wearer and renders unnecessary the process of beating in the stitches when the innersole is used, as in an innersole of the Mackay type, because the stitches sink into the napped surface of the material.

Having fully described my invention, what I claim as new and desire to secure by Letters Patent is:

10 Sheet material for innersoles for shoes

composed of a compressed sheet of tar or asphalt saturated felt, a sheet of heavily napped fabric cemented to one surface of said sheet of felt with the nap face out, and a sheet of woven fabric cemented to the other surface of said sheet of felt.

In testimony whereof I have signed my name to this specification.

GEORGE A. SPEAR.
